DESIGN FOR A BOOT HOOK

Arthur S. Leitner, Los Angeles, Calif.

Application September 7, 1946, Serial No. 133,155

Term of patent 14 years

(Cl. D7—2)

To all whom it may concern:

Be it known that I, Arthur S. Leitner, a citizen of the United States, residing at Los Angeles, in the county of Los Angeles and State of California, have invented a new, original, and ornamental Design for a Boot Hook, of which the following is a specification, reference being had to the accompanying drawing, forming part thereof.

Fig. 1 is a front elevation of a boot hook showing my new design.

Fig. 2 is a side elevation thereof, and

Fig. 3 is a rear view thereof.

I claim:

The ornamental design for a boot hook, substantially as shown and described.

ARTHUR S. LEITNER.
